UNITED STATES PATENT OFFICE.

ALBERT AXBERG, OF MINNEAPOLIS, MINNESOTA.

UMBRELLA.

1,182,617.

Specification of Letters Patent.

Patented May 9, 1916.

Application filed December 2, 1913. Serial No. 804,240.

To all whom it may concern:

Be it known that I, ALBERT AXBERG, a citizen of the United States, residing at Minneapolis, in the county of Hennepin and 5 State of Minnesota, have invented new and useful Improvements in Umbrellas, of which the following is a specification.

The invention relates to an umbrella constructed primarily with a view to its being 10 folded into small compact size when not required for use, while at the same time permitting its convenient and ready extension when desired for its usual purpose.

The main object of the present invention 15 is the provision of an umbrella in which the rod is composed of telescopic sections and the cover frame composed of an inner and outer section slidably connected and adapted for movement in collapsed relation when 20 the umbrella is to be folded and to be extended when the umbrella is open for use.

The invention in its preferred form of 25 details will be described in the following specification, reference being had particularly to the accompanying drawings, in which:—

Figure 1 is a view in elevation showing 30 the umbrella in folded condition. Fig. 2 is a longitudinal sectional view illustrating the handle or rod. Fig. 3 is a detail perspective view showing a portion of an inner and outer rib section and a connector associated therewith. Fig. 4 is an enlarged sectional view through a portion of the rib section to more clearly disclose the sliding connection between the rib sections.

Referring particularly to the accompanying drawings, the improved umbrella 40 comprises a rod 1 including telescopic upper and lower sections 2 and 3, the latter sliding within the former and being adapted when collapsed to reduce the length of the rod to about half its usual length.

Secured upon the upper end of the upper 45 sections 2 is the usual notch 4 having the peripheral recesses 5 for the reception of the ribs, while slidably mounted upon said upper section is the usual runner 6 having 50 the annular flange 7 formed with stretcher receiving notches 8. The runner 7 carries a spring pressed locking dog 9 adapted to co-operate with openings 10 and 11 formed in the upper section 2 of the rod between the 55 ends thereof whereby to secure said runner in elevated or lowered position.

The umbrella ribs are of identical construction, each comprising an inner section 12 and an outer section 13, the inner end of the inner section 12 being formed with 60 the usual eye 14, whereby it may be secured in the notch 4. The inner end of the outer section of the rib is slidably connected to the inner section, through the medium of a connector 15 comprising a U-shaped strip 65 having recessed sides receiving a portion of the inner section with its free ends 15' bent to seat in the groove of the outer section, the strip being soldered or otherwise fixedly secured to said outer section. The 70 respective sections of the ribs are of the usual formation in cross section and the outer section is so disposed that the rounded or unbroken edge thereof seats in the channel of the inner section, the said edge of the 75 outer section being somewhat exaggerated throughout this guiding portion to provide an extending sliding bearing on the inner rib sections. The connector is of such length 80 as to insure a comparatively long contact between the inner and outer rib sections and is so fitted as to maintain this sliding engagement with the respective rib sections under all conditions. The inner ends of the 85 outer rib sections are provided with ears 16, above which are disposed recesses in the connectors to permit the free ends or flanges of the connectors which are seated in the grooves of the outer sections to contact with 90 said ears with which stretchers 17 of the usual type are pivotally connected in the usual manner and to the runner 6.

A cover section 18 is secured to the inner 95 sections of the rib and the similar cover section 19 to the outer section of the ribs, the cover sections being wholly free of connection one with the other, except through the sliding connection of the ribs.

In folding the umbrella the rod sections 100 are telescoped and in the movement of the runner and the lower or inner end of the upper section of the rod the stretchers operate to draw the outer sections of the rod inwardly disposing the cover carried by 105 said section within and beneath the cover carried by the inner sections, whereupon the umbrella may be folded in the usual manner and the parts occupying about half their usual length. In extending the umbrella 110 rod sections are extended and the runner moved upward in the usual manner, the

stretchers forcing the outer sections of the ribs outwardly and moving the cover carried by said sections into a position beyond the cover carried by the inner sections, 5 whereupon the umbrella is in the usual raised form, as will be evident from the drawings.

What is claimed is:—

10 A folding umbrella including a rod, a runner mounted on the rod, channeled ribs having inner and outer sections, tongues formed on the outer rib sections near one end thereof, stretchers connected with said tongues and runner, connectors carried by 15 the inner ends of the outer rib sections

and having recesses disposed above said tongues and the ends of the stretchers connecting therewith, said connectors embracing the inner rib sections, and flanges on said connectors seated in the channels of 20 the outer rib sections with each flange having an end bearing against the edge of a tongue on the outer rib sections.

In testimony whereof I affix my signature in presence of two witnesses.

ALBERT AXBERG.
